METHOD OF AND SYSTEM FOR VAPORIZING
HYDROCARBON LIQUIDS

Sam P. Jones, Dallas, Tex.

Application December 23, 1940, Serial No. 371,364

16 Claims. (Cl. 62—1)

This invention relates to new and useful improvements in methods of and systems for vaporizing hydrocarbon liquids.

The use of hydrocarbon liquids of liquefied gases as fuel for suburban and farm homes has greatly increased during the past few years and has resulted in the development of various systems for vaporizing and otherwise handling these liquids. As is well known, commercial butane, so-called, which is actually a mixture of butane, propane and other hydrocarbons, is most generally employed in these systems.

The accepted type of vaporizing systems now in use (although there may be others) may be classified into two groups, the batch system and the flash system. The batch system employs an underground tank in which the liquid mixture is introduced and gas is drawn from the vapor space above the liquid level in said tank and is conducted to the appliances within the home. In this type of system, no liquid is drawn from the tank but only gas or vapor which is present above the liquid level is taken therefrom. Since the liquid, such as commercial butane is a mixture of different hydrocarbons, the hydrocarbons having the lower boiling point will tend to rise from the liquid body first and will therefore, be withdrawn from the tank first. Thus, as the system continues to operate the liquid mixture is changed, with the result that the calorific value of the fuel supplied to the house appliances is constantly changing, which is most undesirable. The withdrawal of those hydrocarbons having the lower boiling points also results in the heavier ends, with the higher boiling points, remaining in the tank to be withdrawn last. Upon withdrawal of these heavier ends from the tank, said ends tend to condense in the house lines, that is, the conductors from tank to house, in cold weather, because as explained, the boiling point of said ends is considerably higher than the boiling point of the original mixture. This condensation not only creates a hazard but also prevents proper flow of gas to the appliances.

In the flash system, the liquid is stored in an underground tank but the gas is not withdrawn from the vapor space as in the batch system so that the disadvantage of a constantly changing mixture is not had. In the flash system, the liquid itself is drawn from the tank and is passed through a reducing valve and then conducted through a house line to the appliance. The pressure reduction effected by the pressure reducing valve results in vaporization which is enhanced by the flow through the house line which is usual-

ly of considerable length. Although the flash system overcomes the disadvantage of a constantly changing mixture in the tank, it has certain other disadvantages. For example, in the event of a failure of the system to vaporize the liquid, or in the event of overloading of, or excessive demand upon the system, liquid may flow through the house line and into the house appliances. Also, there is a tendency for moisture when present in the fuel to freeze at the pressure reducing valve, with the result that the valve is rendered inoperative to control the flow to the house appliance. Attempts have been made to overcome this freezing by admixing alcohol with the liquid fuel but this is impractical because of the difficulty of properly proportioning the alcohol to the moisture present in the liquid.

Thus, it is evident that both the batch system and the flash system have certain disadvantages which render them inefficient in vaporizing and handling hydrocarbon liquefied gases under all conditions.

It is, therefore, one of the objects of this invention to provide an improved system for hydrocarbon liquids or liquefied gases which overcomes the objections and disadvantages of the batch and flash type systems, while retaining the advantages or desirable features of both.

An important object of this invention is to provide an improved system, of the character described, wherein the liquid is withdrawn from the tank, vaporized and conducted to the appliance under normal operating conditions; said system having means for automatically supplying gas to the appliances from the vapor space above the liquid in the storage tank in the event of an excessive demand or overload of the vaporizing system, or in case of failure of said system for any reason whatever, whereby efficient operation is assured at all times and under abnormal or unusual, as well as normal conditions.

Another object of the invention is to provide an improved hydrocarbon vaporizing system having means for positively preventing the flow of liquid into the appliance or apparatus being supplied, whereby unvaporized liquid cannot pass into the device being supplied with fuel.

A further object of the invention is to provide an improved vaporizing system for hydrocarbon liquids wherein the apparatus being supplied has communication with the stored liquid body and also has communication with the vapor space above said liquid, whereby the apparatus may be supplied from either source, together with control means which is automatically actuated for

normally supplying the apparatus from the liquid which is vaporized in its passage to the apparatus, said control means permitting flow of gas from the vapor space only upon excessive demand or overload on, or failure of the vaporizing equipment.

Still another object of the invention is to provide an improved system, of the character described, wherein the liquid itself in flowing through the house line toward the apparatus being supplied, which condition will occur when an excessive demand is made upon the vaporizing equipment, is utilized to effect the actuation of the control means to provide for a supply of gas from the vapor space above the stored body of liquid, whereby failure of the system to provide fuel is prevented.

Another object of the invention is to provide a hydrocarbon vaporizing system having an improved control means disposed in the conductor between the liquid supply tank and the appliance, said means normally functioning to regulate the pressure of the gas passing therethrough to the appliance and being adapted to function to limit the flow of gas therethrough to the capacity of the vaporizer to deliver a dry saturated gas and thereby prevent passage of liquid to the appliance under abnormal conditions when the demand exceeds the capacity of the vaporizer.

Still another object of the invention is to provide an improved system, of the character described, wherein an auxiliary vaporizer in the form of a heat exchanger may be readily connected in the conductor which establishes communication between the liquid storage tank and the appliance, whereby complete vaporization in colder climates is assured.

A particular object of the invention is to provide an improved method of vaporizing hydrocarbon liquids and supplying the same to an appliance which includes, withdrawing liquid from a stored body of liquid within a tank and vaporizing the same, then conducting the gas so produced to the appliance under normal conditions, and utilizing the presence of an excessive amount of liquid in the conductor to set up a flow of gas from the vapor space above the liquid body whenever the demand is in excess of the capacity of the vaporizing equipment, whereby a constant supply of gas to the appliance is assured at all times.

A construction designed to carry out the invention will be hereinafter described together with other features of the invention.

The invention will be more readily understood from a reading of the following specification and by reference to the accompanying drawings, in which an example of the invention is shown, and wherein:

Figure 1 is a view of a vaporizing system, constructed in accordance with the invention,

Figure 2 is a front elevation of the riser pipe and regulator which is connected in the house line,

Figure 3 is an enlarged, transverse, vertical, sectional view of the upper portion of the riser showing the float valve therein,

Figure 4 is an enlarged, sectional view of the regulator,

Figure 5 is a partial view of a modified form of system showing a heat-exchange vaporizer connected therein,

Figure 6 is an elevation of the vaporizer,

Figure 7 is a transverse, vertical sectional view, taken through the vaporizer, and

Figure 8 is a view, similar to Figure 5, showing another modification of the system.

In the drawings, the numeral 10 designates an underground storage tank for receiving a hydrocarbon liquid which, for the purposes of this description, will be assumed to be commercial butane. As is well known, commercial butane is, in reality, composed of varying percentages of butane, propane and iso-butane and may even contain other hydrocarbons. The storage tank 10 is buried a suitable distance underground and has a curb box 11 extending upwardly from the top of the tank to the surface of the ground. The curb box is normally closed by a suitable cover or closure 12. The tank, together with its various fittings, is of an ordinary construction and the particular details of said tank form no part of the inventive concept of the present invention.

As illustrated, a standpipe 13 extends upwardly from the top of the tank and is enclosed within the curb box 11. A head 14, which carries the various valves, gauges and other devices associated with the filling and operation of the system is mounted on the upper end of the standpipe 13. This head is of the usual construction and may be purchased on the open market. A gas outlet pipe 15 extends through the standpipe 13 and has its lower end communicating with the upper portion of the tank 10. This pipe passes outwardly through a valve 16 mounted in the head 14, whereby gas from the upper end of the tank may be conducted therefrom and through a pressure regulator 17, which regulator is secured to the standpipe within the curb box. A gas line 18 extends from the regulator 17 and has connection with a pipe 19 which extends underground for some distance and then upwardly above the surface, as is clearly shown in Figure 1.

A liquid outlet pipe 20 extends from the bottom of the tank 10 and upwardly into the lower portion of the curb box 11. A hand operated valve 21 is coupled onto the upper end of the liquid outlet line 20 whereby a control of the liquid flowing upwardly through the line 20 from the interior of the tank may be manually controlled. A pressure reducing valve 22 is connected with the housing of the valve 21, whereby a communication between this regulator and the liquid outlet line 20 through the valve 21 is had. The pressure reducing valve 22 is connected with the house line 23, which line parallels the gas line 19 and then extends upwardly to the surface of the ground.

The house line has its end connected in a pressure regulator 24, which regulator is clearly shown in Figure 4. The regulator includes a body or case 25 which is formed with a port 26 at its lower end. The lower portion of the port 26 is internally screw-threaded to receive the house line 23, whereby a flow from the line into the port 26 may occur. A valve seat 27 is formed at the upper end of the port 26 and a pivoted valve element 28 is adapted to engage this seat to close the flow through the port. The valve element is provided with an upwardly extending arm 29, which arm projects through an opening 30 formed within a collar 31. The collar 31 is secured to a flexible diaphragm 32 which has its peripheral portion clamped between the case 25 and a cover 33 which is fastened to the case by suitable screws 34. The cover 33 is formed with an axial, integral sleeve 35 which has its outer end closed by a cap 36. A coil spring 37 has one end engaging the diaphragm 32 while its other

end engages an adjusting nut 38 which is threaded within the sleeve 35 of the case. Manifestly, the coil spring 37 constantly exerts its pressure to move the diaphragm inwardly within the case 25, whereby the arm 29 is urged in a direction tending to open the valve 28 and permit a flow through the port 26. Any pressure within the case 25, of course, acts upon the diaphragm 32 and will tend to move the diaphragm in a direction against the pressure of the spring 37 and thereby urge the valve 28 toward a closed position. By properly adjusting the coil spring 37, it is possible to maintain a predetermined flow past the valve 28 and thereby control the pressure on the downstream side of the regulator 24. It is pointed out that the regulator above described, is of standard construction and is therefore subject to variations. The regulator may be secured to the foundation of the building, or in any other suitable place above the surface of the ground.

A vertical riser pipe 40 has its lower end connected to a swaged nipple 41 which nipple is in turn connected to the upper end of the regulator 24, whereby said riser pipe extends upwardly from the regulator. The upper end of the riser pipe has a T 42 threaded thereon and this T also has connection through a short pipe 43 and an elbow 44 with the gas line 19 which leads from the gas regulator 17 within the curb box 11. Within the interior of the pipe 40 a valve seat 45 is provided and this seat is adapted to be engaged by a resilient valve disk 46 which is secured to the upper end of a float member 47, the latter being disposed within the riser pipe 40. The float is provided with an upwardly extending axial stem 48 which extends through a transverse spider 49 which is preferably a part of the valve seat 45. A coil spring 50, which is relatively light, surrounds the stem above the spider and has its upper end engaging lock nuts 51 which are threaded onto the upper end of the stem. With this arrangement, the float 47 is resiliently supported or suspended within the upper portion of the riser pipe 40 and whenever the liquid level within said pipe rises a sufficient distance to move the float upwardly so as to engage the valve disk 46 with the valve seat 45, a flow from the upper end of the riser pipe is prevented.

The T 42 which is threaded onto the upper end of the riser pipe 40 and which has one side connected with the gas line 19, as has been explained, has its other end connected with the service line 52 which extends through the wall of the house or building and has connection with the particular appliance A which is to be operated.

As has been stated, the system is particularly adapted for use in vaporizing liquefied gases, such as commercial butane. Since commercial butane is composed of varying percentages of different hydrocarbons, each hydrocarbon has a different boiling point at the same pressure and the vapors or gases thereof contain varied heat values. Obviously, the various hydrocarbons and their proportions in the mixture control the boiling point of the mixture and also control the heat value of the vapor which is produced when the mixture is vaporized. When commercial butane is permitted to stand in a tank or other reservoir, under a certain pressure and temperature, vaporization within the reservoir will occur due to the fact that the boiling point of liquid butane is about 33° Fahrenheit. This vaporization will continue until a dormant condition is reached after which no further butane is vapor-

ized so long as the temperature remains the same.

Due to the fact that commercial butane is a mixture of a number of hydrocarbons, the vaporization which occurs when the liquid butane is permitted to stand in a reservoir under certain conditions, is a vaporization of the lighter or more volatile fractions which are present in the mixture. Therefore, the propane and other lighter fractions tend to vaporize more rapidly and the heavier ends tend to remain in a liquid state. If these vapors are constantly withdrawn from the reservoir, it becomes obvious that the gases or vapors so withdrawn are vapors consisting of a mixture which contains the lighter fractions in a predominate volume. Therefore, the gas or vapor which is initially withdrawn from the reservoir would have a predetermined heat value; as the operation continues it will eventually occur that most of the lighter fractions are removed, with the result that the gases or vapors which are drawn from the reservoir as the liquid level falls therein have a different heat value because of the change in the mixture of such gases or vapors. For this reason, it is undesirable to withdraw the gases or vapors from the top of the tank through the line 15 because a constant withdrawal of these gases will result in a change in the mixture and therefore a change in the B. t. u. value of the gas, with the result that constant adjustment of the appliance being supplied is necessary to obtain maximum efficiency.

In the operation of the system and in carrying out the improved method herein, the liquid hydrocarbon, that is, commercial butane, is introduced into the tank 10. The heat from the surrounding earth will of course immediately vaporize a portion of the liquid within the tank and vaporization will continue until a dormant condition is reached. At such time, there will be a certain level of liquid within the tank 10 and above this level, there will be the gases or vapors which have risen from the liquid body. Thus, the space in the upper portion of the tank above the liquid level forms a gas storage chamber.

The pressure regulator 24 which is connected to the house or vaporizing line 23 is set at a pressure which is higher than the pressure for which the gas regulator 17 in the curb box 11 is set. With such arrangement, so long as the pressure within the riser 40 and service line 52 is maintained at the pressure for which the regulator 24 is set, the regulator 17 will remain closed, whereby no gas can flow from the upper end of the tank and into the gas line 19.

When the appliance A is actuated to place a demand upon the system, liquid flows upwardly through the liquid outlet pipe 20 being forced through said pipe by the pressure in the gas storage chamber above the liquid level in the tank. The liquid flowing through the pipe 20 passes through the pressure reducing or expansion valve 22, which brings about a pressure drop resulting in a vaporization of some of the liquid. The vapors so produced, together with the remaining liquid flow through the vaporizing or house line 23 toward the regulator 24. The heat of the earth surrounding the vaporizing line 23 is sufficient to vaporize the liquid flowing therethrough under normal operating conditions. In other words, the length and size of the line 23 is predetermined, whereby a certain number of cubic feet per hour of gas may be produced through this line. By lengthening or

shortening the line 23, the capacity of the system may be varied.

By the time that the liquid reaches the end of the vaporizing line 23, all of said liquid is vaporized and the vapors or gases pass through the regulator 24 which, as has been explained, is adjusted to maintain a predetermined pressure beyond the regulator, whereby gas under a predetermined pressure is supplied to the appliance A. As a practical example, the regulator may be set for seven (7) ounces, whereby the gas or vapor supplied to the appliance is under this pressure. This would result in seven (7) ounces pressure being present not only in the service line 52 but also in the gas line 19 in advance of the regulator 17 within the curb box 11. If the regulator 24 is set for seven (7) ounces, then the regulator 17 in the curb box will be set at a less pressure, for example, six (6) ounces, with the result that so long as seven (7) ounces pressure is maintained within the service line 52 and the gas line 19, the regulator 17 will not function but will hold the gas line closed. Under such condition, no gas can flow from the gas storage chamber in the upper end of the tank 10 to the gas line 19 and then to the service line 52.

So long as the demand of the appliance or appliances which are being operated does not exceed the capacity of the system to supply gas, then said system operates in the manner above described. That is, liquid is withdrawn through the pipe 20, taken through the pressure reducing or expansion valve 22, then through the house line 23, regulator 24, riser pipe 40 and to the service line 52. Manifestly, at this time under normal operating conditions, the gas or vapor which is passing through the regulator 24 is acting upon the diaphragm 32 to affect a control or regulation of the pressure in accordance with the adjustment of the spring 37.

Whenever the demand is increased to a point beyond the capacity of the vaporizing apparatus, gas is withdrawn from the vaporizing line 23 faster or more rapidly than the liquid is vaporized in said line, with the result that liquid will flow through the vaporizing line 23 toward the regulator 24. If the excessive demand continues, all of the gas will be withdrawn from the vaporizing line and the liquid will eventually reach the regulator 24, such liquid entering the casing 25 of said regulator through the port 29. As soon as liquid enters the casing 25, it will begin to rise within said casing and the weight of the column of liquid within said casing will act against the diaphragm 32, such weight being added to the vapor pressure acting against said diaphragm. It will be evident that as soon as the weight of a column of liquid begins to act upon the diaphragm 32, the pressure of the vapor or gas which passes into the riser pipe 42 and then into the service pipe 52 will be reduced in accordance with the amount of pressure exerted on the diaphragm by such column of liquid. A continued demand for gas in excess of the capacity of the vaporizing means will continue to build the liquid column up within the regulator 24 and this rise in liquid level will continue until such time as the pressure passing to the appliance through the riser 40 and service pipe 52 drops to a predetermined point in accordance with the setting of the regulator 17. As was previously pointed out, if the regulator 24 is set to maintain a pressure of seven (7) ounces, while the regulator 17 is set to maintain a pressure of six (6) ounces, it will be manifest that when the liquid level rises within the

regulator 24 to a point where the weight of the liquid column is equal to 1 ounce pressure, then the vapor pressure in the service line 52 will drop to six (6) ounces or slightly below. When this occurs, the regulator 17 is automatically opened, whereby gas may flow from the gas storage chamber in the upper end of the tank 10 through the line 15, then through the regulator 17 and to the gas line 19. From the gas line, the gas will pass to the service line 52 to supply the appliance A. As soon as the regulator 17 opens to permit a flow of gas or vapor from the gas storage chamber of the tank, any further liquid level rise within the regulator or riser pipe will be prevented and operation of the appliance will continue in this manner so long as the excessive demand, or the demand in excess of the capacity of the vaporizing line 23 remains.

From the foregoing, it will be seen that under normal conditions gas is supplied from the vaporizing line 23, with the result that a gas having a constant B. t. u. value is supplied to the appliance. When the demand becomes excessive, that is when more gas is required than the vaporizing equipment can produce, then the regulator 17 is automatically opened to supply gas or vapor from the gas storage chamber of the tank.

As soon as the demand for gas or vapor decreases, a building up of the pressure within the service line 52 and within the riser 40, as well as within the gas line 19, will take place and when this pressure is built back up to the pressure in excess of that for which the regulator 17 is adjusted, then said regulator automatically closes to shut off the flow from the gas storage chamber to the service line, as explained. After the regulator 17 closes, the gas is again supplied solely from the vaporizing line 23.

The decrease in the demand for gas permits the liquid within the vaporizing line 23 to be converted into a gas by the earth's heat prior to its passage to the regulator 24. In fact, all of the liquid in the line 23 is vaporized some distance before it reaches said regulator, whereby the gas in passing through the vertical portion of the line 23 will be superheated since the pipe is at a higher temperature than the gas. This superheated gas passes upwardly through the liquid column which had previously accumulated within the diaphragm case and due to its superheated condition, is capable of picking up some of the liquid in the column as it passes upwardly therethrough. Continued operation under a condition where the demand is below the capacity of the vaporizer permits all the liquid to be picked up by the gas passing through the liquid column and in a short time, all of the accumulated liquid has been dissipated and converted into a gas. Of course, after the liquid has been removed in this manner, operation of the system continues in a normal manner, with the gas being supplied from the vaporizing line 23. It will be evident that the regulator 24 and riser pipe assembly 40 performs two definite functions. Under normal operating conditions, said regulator regulates the pressure on the gas passing through from the vaporizer to the appliance at all rates of flow below the capacity of said vaporizer; when the demand exceeds the capacity of the vaporizer, the regulator serves to limit the flow of vapor therethrough to the capacity of the vaporizer to deliver a dry saturated vapor and, therefore, it is never possible for liquid to be carried over into the service line and to the appliance. Whenever the liquid builds up a predetermined amount above

the regulator diaphragm 32, the gas regulator 17 in the curb box 11 automatically opens to supply gas from the gas storage chamber of the tank 10. Gas is supplied from this chamber until such time as the excessive demand decreases, at which time the system returns to normal operation.

Under some conditions, the moisture in the liquid fuel may cause the regulating valve 24 to freeze and thereby shut off a flow from the line 23 to the service line 52. If this should occur, a drop in pressure in the service line 52 will immediately follow and as soon as this pressure drops to a point below that for which the gas regulator 17 in the curb box is set, said regulator 17 will immediately open to supply gas to the appliance from the gas storage chamber of the tank 10. The heat of the earth will eventually thaw the freezing at the regulator 24 to permit a resumption of flow from the line 23 to the service line. As soon as the freezing condition is overcome, the gas regulator 17 automatically closes and normal operation is resumed. Thus, it will be obvious that regardless of the condition which might cause a reduction in the pressure of the service line 52, the regulator 17 in the curb box 11 will automatically open to permit a flow of gas from the storage chamber of the tank to the appliance, whereby continuous uninterrupted supply to said appliance is maintained at all times.

There may be instances where the gas regulator 17 may not properly function upon a reduction of pressure in the service line 52 due to the building up of a liquid column behind the diaphragm 32 of the regulator 24. If the gas regulator 17 failed to open to supply gas to the service line 52, the liquid level would continue to rise in the pipe 40 and in order to prevent a flow of this liquid into the service line under these conditions, the float 47 is provided in the upper end of said riser. Manifestly, as the liquid level builds up in the riser to a sufficient distance, it will cause the float 47 to move upwardly, whereby the valve disk 46 on the upper end of said float engages the valve seat 45 to completely shut off a flow from the vaporizing line 23 to the service line 52. In such case, the system would be entirely shut down, advising the operator that some of the mechanism is not properly functioning. The provision of the float will positively prevent the passage of liquid into the service line 52 under any condition.

In Figures 1 to 4, the liquid which is withdrawn from the tank 10 through the outlet pipe 20 is vaporized by means of the pressure reducing or expansion valve 22 which is located in the lower portion of the curb box 11, together with the heat of the earth acting upon the vaporizing line 23. In the colder climates, the earthen heat may not be sufficient to accomplish complete vaporization and it might be desirable to employ an auxiliary vaporizing unit. Such an arrangement is shown in Figures 5 to 7. Referring to these figures, a vaporizer 60 which includes an annular case 61 having a plurality of coils 62 therein, is provided. The vaporizer is secured by bolts 63, or other suitable means, to the outer face of the regulator case 25. One end of the coils 62 has connection with an inlet collar 64 (Figure 6) to which a line 23a is connected. The other end of the line 23a has connection with the vaporizing line 23 which leads from the tank 10, whereby liquid from the tank is conducted to the coils 62 of the vaporizer 60. The other end of the coils 62 has connection with an outlet conductor or

tube 65 which tube leads to an expansion valve 66 which is substituted for the expansion valve 22 shown in the first form. The expansion valve 66 is connected by a suitable coupling 67 with the inlet port 26 of the diaphragm case 25.

For heating the coils 62, hot water may be circulated through the annular casing 61 of the vaporizer being introduced through an inlet pipe 68 and being conducted therefrom by an outlet pipe 69. The pipes 68 and 69 may be connected with the water system of an ordinary hot water heater H which is normally used within a house or home for heating the water supply. Of course, it is evident that the hot water which is circulated through the vaporizer may be obtained from any suitable source.

The operation of this system is substantially the same as the system shown in Figures 1 to 4. However, instead of the expansion valve 22 being located within the curb box, the expansion valve 66 is interposed between the vaporizer 60 and the regulator 24. The liquid is conducted from the tank 10 and is carried through the coils 62 of the vaporizer, where it is converted into a gas. It is then taken through the pressure reducing valve 66 and brought down to the desired pressure, after which said gas passes through the regulator 24 and then into the riser 40 and T 42. From the T, the gas is conducted through a line 43a which connects the T with the gas line 19, such connection being effected by a T 70. The service line 52 is also connected in the T 70, whereby gas may be supplied either through the line 43a or through the gas line 19, when the regulator 17 is actuated, as has been explained above.

A slightly modified form of the hook-up shown in Figure 5 is illustrated in Figure 8. It may be desirable under certain conditions to positively circulate the hot water through the vaporizer 60 under pressure and for this purpose a water pump 75 may be connected in the water inlet line 68 leading to the vaporizer 60. In this hook-up, the upper end of the riser 40 carries the T 42 which has the service line 52 extending therefrom. The other side of the T is connected by the pipe 43 and elbow 44, shown in Figure 1, to the gas line 19. The only difference between this hook-up and that shown in Figure 5, with the exception of the interposition of the pump 75 is that the service line 52 leads from the T 42 at the upper end of the riser 40 instead of from the T 70 which is connected in the gas line 19. In Figure 8, one end of the T 70 is plugged, whereas in Figure 5 one side of the T 42 is plugged. Manifestly, the operation of the system shown in Figure 8 is exactly the same as in the other forms.

What I claim and desire to secure by Letters Patent is:

1. A vaporizing system including, a storage tank having a hydrocarbon liquid stored therein, a gas chamber communicating with the upper end of the tank for receiving the vapors rising from said stored body of liquid, a supply conductor extending from the tank for conducting liquid therefrom, means for vaporizing the liquid passing through said conductor to produce a gas, means connected in the conductor for regulating the pressure of the gas passing from the conductor to maintain a predetermined pressure in said conductor beyond said regulating means, means for establishing communication between the conductor beyond said regulating means and the gas chamber, and a valve in said last-named

means normally closed to prevent flow of gas from the gas chamber to the conductor, said valve being responsive to pressure in the conductor and being automatically opened when the pressure in the conductor falls below a predetermined point.

2. A vaporizing system including, a storage tank having a hydrocarbon liquid stored therein, a gas chamber communicating with the upper end of the tank for receiving the vapors rising from said stored body of liquid, a supply conductor extending from the tank for conducting liquid therefrom, means for vaporizing the liquid passing through said conductor to produce a gas, means connected in the conductor for regulating the pressure of the gas passing from the conductor to maintain a predetermined pressure in said conductor beyond said regulating means, a riser associated with said regulating means for receiving liquid in the event liquid flows past said regulator, the liquid in said riser acting upon the regulating means to vary the pressure in the conductor beyond the regulator, means for establishing communication between the conductor beyond said regulating means and the gas chamber, and pressure responsive means for controlling the flow of gas from the chamber to the conductor and actuated when the pressure in the conductor falls below a predetermined point.

3. A vaporizing system including, a storage tank having a hydrocarbon liquid stored therein, a gas chamber communicating with the upper end of the tank for receiving the vapors rising from said stored body of liquid, a supply conductor extending from the tank for conducting liquid therefrom, means for vaporizing the liquid passing through said conductor to produce a gas, means connected in the conductor for regulating the pressure of the gas passing from the conductor to maintain a predetermined pressure in said conductor beyond said regulating means, a riser associated with said regulating means for receiving liquid in the event liquid flows past said regulator, the liquid in said riser acting upon the regulating means to vary the pressure in the conductor beyond the regulator, means for establishing communication between the conductor beyond the riser and the gas chamber, and a valve in said last-named means normally closed to prevent flow of gas from the gas chamber to the conductor, said valve being responsive to pressure in the conductor and being automatically opened when the pressure in the conductor falls below a predetermined point.

4. A vaporizing system including, a storage tank having a hydrocarbon liquid stored therein, a gas chamber communicating with the upper end of the tank for receiving the vapors rising from said stored body of liquid, a supply conductor extending from the tank for conducting liquid therefrom, means for vaporizing the liquid passing through said conductor to produce a gas, means connected in the conductor for regulating the pressure of the gas passing from the conductor to maintain a predetermined pressure in said conductor beyond said regulating means, means for establishing communication between the conductor beyond said regulating means and the gas chamber, means for controlling the flow of gas from the chamber to the conductor and actuated when the pressure in the conductor falls below a predetermined point, and means associated with the regulating means in the supply conductor for utilizing any unvaporized liquid which passes said regulating means to act upon

said regulating means and thereby reduce the pressure in the conductor beyond the regulating means and thereby affect an actuation of the control means.

5. A vaporizing apparatus for liquefied gases including, a liquid reservoir, a gas chamber communicating with the upper portion of the reservoir for storing gas vaporized from the body of liquid, a supply conductor leading from the reservoir for conducting liquid from said reservoir, means in said conductor for vaporizing the liquid passing therethrough, a regulator connected in said conductor beyond the vaporizing means to maintain a predetermined pressure in said conductor, a connecting line between the gas chamber and the supply conductor beyond the regulator, and control means mounted in said line for controlling the flow of gas from the gas chamber to said conductor, said control means responsive to the pressure in said conductor being normally closed and being moved to an open position only when the pressure in the conductor falls below a predetermined point.

6. A vaporizing apparatus for liquefied gases including, in combination with a gas operated appliance, an underground liquid storage tank, a gas chamber communicating with the upper portion of the tank for storing the gas vaporized from the body of liquid, a supply conductor extending from the tank to the appliance and having a portion thereof underground, whereby the heat of the earth aids in vaporizing liquid flowing through said conductor, means in the conductor for enhancing vaporization of the liquid, a regulator in the conductor for maintaining the pressure of the gas flowing to the appliance substantially constant, and means actuated irrespective of the pressure within the tank for supplying gas from the gas chamber to the appliance in the event the pressure of the gas supplied from the conductor falls below a predetermined point.

7. A vaporizing apparatus for liquefied gases including, in combination with a gas operated appliance, an underground liquid storage tank, a gas chamber communicating with the upper portion of the tank for storing the gas vaporized from the body of liquid, a supply conductor extending from the tank to the appliance and having a portion thereof underground, whereby the heat of the earth aids in vaporizing liquid flowing through said conductor, means in the conductor for enhancing vaporization of the liquid, a regulator in the conductor for regulating the pressure of the gas and maintaining the same at a predetermined point, means associated with the regulator for receiving liquid in the event liquid passes said regulator and for causing said liquid to act upon the regulator to produce a drop in the maintained pressure beyond the regulator, and means actuated by such pressure drop for supplying gas from the gas chamber to the appliance.

8. A vaporizing apparatus for liquefied gases including, in combination with a gas operated appliance, an underground liquid storage tank, a gas chamber communicating with the upper portion of the tank for storing the gas vaporized from the body of liquid, a supply conductor extending from the tank to the appliance and having a portion thereof underground, whereby the heat of the earth aids in vaporizing liquid flowing through said conductor, means in the conductor for enhancing vaporization of the liquid, a regulator in the conductor for regulating the pressure of the gas and maintaining the same at

a predetermined point, means associated with the regulator for receiving liquid in the event liquid passes said regulator and for causing said liquid to act upon the regulator to produce a drop in the maintained pressure beyond the regulator, a connecting line extending from the gas chamber to the supply conductor beyond the regulator, and control means in said line normally closed and arranged to be opened when the pressure in the conductor beyond the regulator falls below a predetermined point to permit a flow of gas from the gas chamber to the appliance.

9. A vaporizing apparatus for liquefied gases including, a liquid reservoir, a gas chamber communicating with the upper portion of the reservoir for storing gas vaporized from the body of liquid, a supply conductor leading from the reservoir for conducting liquid from said reservoir, means in said conductor for vaporizing the liquid passing therethrough, a regulator connected in the conductor beyond the vaporizing means to maintain the pressure of the gas flowing from the conductor at a predetermined point, a vertical riser pipe connected in the conductor adjacent the regulator and communicating with the interior thereof, said riser functioning to collect liquid in the event liquid passes the regulator and cause it to act upon the regulator to reduce the pressure of the gas flowing from the conductor, and means actuated by the reduction in pressure in the conductor for supplying gas from the gas chamber to said conductor beyond the regulator.

10. A vaporizing apparatus for liquefied gases including, a liquid reservoir, a gas chamber communicating with the upper portion of the reservoir for storing gas vaporized from the body of liquid, a supply conductor leading from the reservoir for conducting liquid from said reservoir, means in said conductor for vaporizing the liquid passing therethrough, a regulator connected in the conductor beyond the vaporizing means to maintain the pressure of the gas flowing from the conductor at a predetermined point, a vertical riser pipe connected in the conductor adjacent the regulator and communicating with the interior thereof, said riser functioning to collect liquid in the event liquid passes the regulator and cause it to act upon the regulator to reduce the pressure of the gas flowing from the conductor, a connecting line between the gas chamber and the supply conductor beyond the regulator, and a regulator in said line set to open at a pressure below the pressure at which the regulator in the conductor is set, whereby a reduction in the normally maintained pressure in the conductor actuates the regulator in the connecting line to permit a flow of gas from the gas chamber to said conductor.

11. A vaporizing apparatus for liquefied gases including, a liquid reservoir for receiving a hydrocarbon liquid, said reservoir having a gas chamber for storing the gas rising from the stored body of liquid, a liquid conductor leading from the reservoir, a gas line leading from the gas chamber, a supply pipe connected with both the liquid conductor and the gas line, means for vaporizing the liquid in the liquid conductor to produce gas, regulating means in conductor in advance of the supply pipe for regulating the pressure of the gas flowing to said pipe, and regulating means in the gas line between the gas chamber and the supply pipe, said last named means being set at a lower pressure than that for which the regulating means in the liquid con-

ductor is set, whereby so long as the normal pressure is maintained in the supply pipe by the regulator in the liquid conductor, flow through the gas line is shut off.

5 12. A vaporizing apparatus for liquefied gases including, a liquid reservoir for receiving a hydrocarbon liquid, said reservoir having a gas chamber for storing the gas rising from the stored body of liquid, a liquid conductor leading from the reservoir, a gas line leading from the gas chamber, a supply pipe connected with both the liquid conductor and the gas line, means for vaporizing the liquid in the liquid conductor to produce gas, regulating means in conductor in advance of the supply pipe for regulating the pressure of the gas flowing to said pipe, and means associated with the regulating means in the liquid conductor for collecting liquid and causing it to act upon said regulating means to reduce the pressure in the supply pipe, whereby the regulating means in the gas line is actuated to supply gas from the gas chamber in the event liquid reaches the regulating means in the conductor.

25 13. The method of vaporizing gases for use in actuating a gas operated appliance which includes, confining a body of liquid and accumulating the gases which rise from the stored body of liquid, conducting a portion of the liquid from the confined body and vaporizing the same to produce gas in addition to the gas rising from the body, regulating the pressure of the produced gas and conducting the same to the appliance to be actuated, and supplying gas from the accumulated gas when the pressure of the gas beyond the regulator falls below a predetermined point.

30 14. The method of vaporizing gases for use in actuating a gas operated appliance which includes, confining a body of liquid and accumulating the gases which rise from the stored body of liquid, conducting a portion of the liquid from the confined body and vaporizing the same to produce gas in addition to the gas rising from the body, regulating the pressure of the produced gas and conducting the same to the appliance to be actuated, utilizing the weight of the liquid in the event said liquid reaches the regulating apparatus to affect a pressure drop beyond said regulating apparatus, and conducting gas from the accumulated gases above the stored body of liquid to the appliance when a predetermined pressure drop occurs in the system beyond the point of regulation.

35 15. A vaporizing system including, a storage tank having a hydrocarbon liquid stored therein, a gas chamber communicating with the upper end of the tank for receiving the vapors rising from said stored body of liquid, a supply conductor extending from the tank for conducting liquid therefrom, means for vaporizing the liquid passing through said conductor to produce a gas, means connected in the conductor for regulating the pressure of the gas passing from the conductor to maintain a predetermined pressure in said conductor beyond said regulating means, means for establishing communication between the conductor beyond said regulating means and the gas chamber, and means responsive to the pressure in said conductor for controlling the flow of gas from said chamber to the conductor, the pressure responsive means being normally in a closed position and actuated when the pressure in said conductor falls below a predetermined point.

40 16. A vaporizing apparatus for liquefied gases including, a liquid reservoir, a gas chamber com-

municating with the upper portion of the reservoir for storing gas vaporized from the body of liquid, a supply conductor leading from the reservoir for conducting liquid from said reservoir, means in said conductor for vaporizing the liquid passing therethrough, a regulator connected in said conductor beyond the vaporizing means to maintain a predetermined pressure in said con-

5 ductor, a connecting line between the gas chamber and the supply conductor beyond the regulator, and control means mounted in the line normally in a closed position and actuated by a predetermined pressure drop in said conductor for controlling the flow of gas from said gas chamber to the conductor.

SAM P. JONES.
